UNITED STATES PATENT OFFICE.

CAMILLE CONTAL, OF ST. CLOUD, FRANCE.

GEARING.

1,129,457.

Specification of Letters Patent. Patented Feb. 23, 1915.

Application filed September 3, 1913. Serial No. 787,829.

To all whom it may concern:

Be it known that I, CAMILLE CONTAL, a citizen of the Republic of France, residing at 6 Avenue Magenta, St. Cloud, Seine 5 et Oise, in the Republic of France, have invented certain new and useful Improvements in Gearing, of which the following is a specification.

My invention relates to certain improvements in multiplying gearing, and more particularly to a type adapted to be driven by hand, and moved about during the operation.

In making my invention, I had in mind 15 particularly, vacuum cleaner apparatus, in which the air pump or blower employed for creating the desired degree of vacuum is driven by hand. My invention is not limited to vacuum cleaner apparatus, as it may be 20 employed in connection with various other forms of apparatus, particularly where it is important to secure a high degree of speed multiplication, and at the same time keep the frictional resistance of the working 25 parts as low as possible.

When employed in a vacuum cleaner apparatus, the pump or blower is preferably mounted at one end of a tube or helve and adjacent the suction nose-pipe, while the 30 multiplying gearing and the handle for driving the same are located at the opposite end of the tube or helve. The two are connected by a shaft extending lengthwise of the said helve, and thus as the shaft is rotated at high speed, it is subjected to only a 35 comparatively small torsion, and can thus be very lightly constructed. The character of the mechanism driven by the shaft forms no portion of my present invention, and it 40 is therefore immaterial whether the helve be straight, curved, or articulated, or whether the shaft be rigid, flexible, or provided with universal joints.

In some forms, the multiplying gearing 45 may be disposed closely adjacent to the mechanism to be driven so that the main connecting shaft will be comparatively short.

One specific embodiment of my invention 50 is illustrated in the accompanying drawings to which reference is to be had, and in which similar reference characters indicate corresponding parts in the several views. This specific embodiment as well as 55 the drawings and description thereof, are to be considered in an illustrative sense as va-

rious changes may be made in the construction and arrangement of the parts, within the scope of the appended claims, without departing from the spirit of my invention.

In these drawings, Figure 1, is a side elevation of a vacuum cleaner apparatus having a driving mechanism constructed in accordance with my invention, the lower portion of the apparatus being shown in section. Figs. 1^a and 1^b show modified forms of the suction nose-pipe. Figs. 2 and 3 are axial sections of the upper portion of the apparatus. Fig. 4 is an elevation of the dust collecting bag turned inside out.

In the drawings, 1 designates a tube constituting the helve of the apparatus and carrying at its lower end a cylindrical casing 2 and at its upper end a hemispheric casing 3; the former inclosing the blower 4 and the latter the speed multiplier. Such multiplier comprises a gear wheel 5 having a crank-handle 6, two pinions 7 meshing with such wheel, two frictional disks or plates 14 associated with such pinions and an anti-friction roller 8 secured to the shaft 9 of the blower, which is located within the tube 1.

The wheel 5 is of hemispheric shape corresponding to that of the casing 3, to which it serves as a lid; such wheel is mounted on a spindle 10 which passes through a socket 11 integral with the casing 3. Both the pinions 7 with which it meshes are located on two spindles 12 secured on the one hand to the casing 3 and on the other hand to the lateral bosses of the socket 11; they are subjected to the action of springs 13, which press the plates 14 onto the opposite sides of the roller 8. The upper part of the shaft 9 is journaled in a piece 26^a which is so guided in the casing 3 as to be enabled to slide freely in a direction parallel to the axis of the plates 14. By means of such freedom, the roller 8 and the plates 14 are enabled to move slightly under the influence of the 100 pressures of the springs 7, so that such pressures are made equal automatically, as well as the tangential strain on the roller 8, which avoids any pushing of the shaft 9 on its guide 26^a; the friction is thus rendered negligible notwithstanding the high speed rotation of the shaft.

15 designates the arms or braces which hold the socket 11 rigidly in the casing 3.

A handle 16 is screwed to such casing and 110 forms a prolongation of the socket 11; it is preferably hollow, to contain a lubricant.

The blower casing 2 is open at its lower part and receives removably any one of the suction nose-pipes 17, 18 or 19 shown in Figs. 1, 1^a and 1^b; the nose-pipe 17 is upwardly curved and carries a flexible pipe 20 terminating in a rigid tube having a sucker cup which can be applied to and moved on the hangings, tapestry, the furniture and the like; the nose-pipe 18 terminates at the bottom in an elongated sucker cup which serves to clean the carpets; the nose-pipe 19 has a narrow sucker cup 22 more particularly designed to clean arm-chairs and other such parts of the furniture.

15 The different nose-pipes are secured alternatively to the opening of the casing 3, for instance by means of screws 23 carried by hangers having bent ends and which are articulated to the said casing, only one of such hangers being visible in the drawings. The air loaded with dust, sucked in by the blower, escapes from the casing 2 through a pipe 25 and is received in a bag 26.

To clean a carpet, for instance, the casing 25 3 is provided with the nose-pipe 18, and the apparatus is so operated as to apply the sucker cup 21 to the carpet and then to move the same over the entire surface of such carpet while turning the blower at the same 30 time; for such purpose, the crank-handle 6 will be turned by the right hand and the handle 16 will be held by the left hand so as to afford the required support; the operator will be able to push the apparatus easily 35 forward by bearing his breast against the plate 27, which is mounted on the casing 3 by means of a knee-cap joint 28. If required, the weight of the upper part of the apparatus may be transferred in part onto 40 the shoulders of the operator by means of a strap hooked to such upper part; such strap not being shown in the drawings.

The rotation speed of the handle 6 is multiplied in the first place by the wheel 5 45 and the pinions 7 and a second time by the plates 14 and the roller 8, so that the blower revolves very quickly with energetic action. The passive resistances are weak ones, by reason of the simplicity of the controlling 50 means and the peculiar construction of the speed multiplier. Such resistances may, moreover, be further diminished by the addition of ball-bearings. Again, the oiling of all the frictional parts can be easily secured, for instance by means of the lubricant placed in the handle 16 and oiling devices placed on the bearings of the shaft 9. Such conditions allow the construction of a 55 very efficient apparatus and one which works smoothly. Furthermore, the arrangement of all the elements of the mechanism such as the gearing, the shaft, the blower, within a tube and casing forming a compact covering, makes the hereinbefore 60 described cleaning device a self-contained 65

apparatus which is proof against outside shocks, does not get out of order, offers no danger to those persons which use the same and which is very compact.

The dust collecting bag 26 has an opening 70 at its upper part, the edges of which are provided with a metal clasp 29 articulated at 30. Such opening is normally held closed by means of a clip 31, hanging by a chain or wire from the helve 1.

75 The lower end of the bag is provided with an opening for the passage of a rigid tube 33 and is secured around such tube by a binding 34. The outer part of the said tube is engaged with a little friction in the pipe 80 25; while its inner part, which extends within the bag, is provided with a deflecting cone 35 and a bail 36 which allows the passage of a finger. Such means allow of turning the bag readily inside out to get rid of all 85 the dirt after having withdrawn the tube 35 from the pipe 25 and opened the clip 31, the top of the bag is opened and lowered, while the bottom of the tube 33 is resting on the floor or other support, until the bail 36 90 can be easily caught; the turning of the bag can then be readily finished by pulling the bail upward and the clasp 29 downward (see Fig. 4). The deflecting cone 35 is not 95 essential.

Without departing from the invention one can, of course, modify the shape of the casings 2 and 3, as well as that of the blower 4 and the different sucker nose-pipes; in the same way, there may be used a speed multiplier of any suitable construction, comprising if required several gearings located at different points of the apparatus.

Claims—

1. In apparatus of the kind described, the 105 combination of a tubular sleeve, an arbor or shaft within such sleeve, a friction-roller on the upper end of said shaft, a gear-casing on the upper end of the sleeve, two friction-plates located on the opposite sides of the 110 friction-roller, and means whereby to revolve such plates in inverse directions.

2. An apparatus of the kind described comprising the combination of a tubular helve, a gear casing on one end of such 115 helve, a socket integral with such casing and extending across the axis of the said tubular helve, a revolving spindle in such socket, a miter wheel on such spindle, a handle on such wheel, two stationary axles in the casing on the sides of the said socket, two pinions revolving on such axles and meshing with the said wheel, two frictional plates associated with such pinions, a shaft extending into the tubular helve, a roller on such shaft 120 and between the two plates, and springs pressing such plates against such roller.

3. An apparatus of the kind described comprising the combination of a tubular helve, a shaft extending into such helve, a 125

- roller on such shaft, a gear casing on the tubular helve, such casing having a socket extending across the helve, a slideable guide in such socket and adapted to guide the said shaft which passes through the said socket, two stationary spindles in the said gear-casing, frictional plates revolving on such spindles and engaging the said roller on the two opposite sides, two springs compressed respectively between two opposite sides of the casing and both the said plates, and means whereby to revolve such plates. 5
4. In apparatus of the kind described, the combination of a tubular sleeve, a gear-casing secured to one end of such sleeve, such casing having a large lateral opening, a gear-wheel rotatably arranged on such opening and forming a lid for the casing, a crank on the said wheel, a shaft within the sleeve, and means located in the casing for transmitting the rotation of such wheel to the said shaft. 10
5. In combination a gear casing, a wheel constituting a lid therefor, a pinion engaging with said wheel and driven thereby and rotatable about an axis at right angles to that of the wheel, a second wheel rigid with the said pinion and a pinion engaging with said second mentioned wheel and driven thereby, and rotatable about an axis at right angles to the axis of said first mentioned pinion. 15
6. In combination, a substantially hemispherical gear casing, a substantially hemispherical wheel constituting a lid therefor, a shaft projecting into said casing, in a direction substantially at right angles to the direction of rotation of said wheel, a pinion on said shaft, and two power transmitting members rotatable in opposite directions and engaging with said pinion and with said first mentioned wheel. 20
7. In combination, a substantially hemispherical gear casing, a substantially hemispherical wheel, constituting a lid for said casing, a shaft projecting into said casing and having a pinion and a miter wheel and miter pinion within said casing, said miter wheel having engagement with said first mentioned pinion and said miter pinion engaging with said first mentioned wheel. 25
8. In combination, a portable gear casing having a handle, a rotatable wall section diametrically opposed to said handle, a handle for rotating it about an axis in alinement with the latter, a shaft projecting into said casing in a direction substantially at right angles to said first mentioned handle, and means for rotating said shaft upon the rotation of said wall section. 30
9. A portable gear casing, having a supporting handle, a miter wheel having a handle projecting therefrom, and by which said wheel may be rotated, a shaft projecting into said casing and having a pinion thereon and a combined miter gear and miter pinion, the latter having engagement with said first mentioned wheel, and the former having engagement with said first mentioned pinion. 35
10. In combination, a gear casing, a shaft projecting into said casing, and having a friction roller on its inner end, two friction plates located on opposite sides of said friction roller and a rotatable driving member for rotating said friction plates in opposite directions. 40
11. In combination, a gear casing having a large lateral opening, a gear wheel rotatably arranged at said opening and forming a lid for said casing, a crank on said wheel, a shaft projecting into said casing and means within said casing for transmitting the rotation of said wheel to said shaft. 45

In testimony, that I claim the foregoing as my invention I have signed my name in presence of two subscribing witnesses.
